US00D756771S

(12) **United States Design Patent**
Covey et al.

(10) **Patent No.:** **US D756,771 S**
(b4) **Date of Patent:** **** May 24, 2016**

(54) **SERVING CUP**

(71) Applicant: **Food & Beverage Innovations, LLC**,
Portland, OR (US)

(72) Inventors: **Jason Covey**, Seattle, WA (US); **Ian Graves**, Seattle, WA (US); **Thomas Gurski**, Seattle, WA (US)

(73) Assignee: **Food & Beverage Innovations, LLC**,
Portland, OR (US)

(**) Term: **14 Years**

(21) Appl. No.: **29/514,408**

(22) Filed: **Jan. 12, 2015**

(51) LOC (10) Cl. **09-07**

(52) U.S. Cl. **D9/428; D9/424; D9/425; D7/400; D7/545**
